UNITED STATES PATENT OFFICE.

AMBROISE MILLOT, OF ZURICH, SWITZERLAND.

GRINDING-MILL.

SPECIFICATION forming part of Letters Patent No. 416,371, dated December 3, 1889.

Application filed August 1, 1888. Serial No. 281,709. (No model.)

To all whom it may concern:

Be it known that I, AMBROISE MILLOT, manufacturer, of Zurich, in the Republic of Switzerland, have invented Improvements in 5 Grinding-Mills, of which the following is a specification.

The object of this invention is to provide an efficient and economical apparatus for decorticating, splitting, reducing, and cleaning 10 corn or other grain or seed, removing from it impurities—such as poppy-seeds, smut, and the like—with but little waste of the good material. I will describe it as applied to the 15 treatment of corn, from which its general application will also be well understood.

In the accompanying drawings, Figure 1 is a vertical section. Fig. 2 is a side elevation, and Fig. 3 is partly a plan and partly a horizontal section of an apparatus arranged according to this invention. Fig. 4 is an under side view of the cover of the apparatus fitted with the working-surfaces. Figs. 5 and 6 are sections on a larger scale of the lower and upper disks taken on lines 5 5 6 6, respectively.

The corn to be treated is introduced by the hopper A, which is capable of being raised and lowered by the hand-wheel B and screw working on a screw outside the hopper A. The 20 corn is scattered by the rotary distributing-plate c over the sieve or grating D, by which foreign bodies larger than the grains of corn are kept from entering into the apparatus. After passing through openings H in a ring 25 J the corn is drawn between two grinding-disks E and F. The upper disk F is made up of segments of cast-iron, tempered steel, porcelain, flint, granite, or any other suitable hard material, which segments are attached 30 (by means of screws, for instance) to the lid F', fixed to the frame U of the apparatus. The segments F are provided with grooves of any suitable width and depth and at any desired angle. The lower disk E is composed 35 of segments, also of hard material, and having any desired number of projections and spaces forming the working-surfaces of the apparatus, as shown in Figs. 3 and 5. The segments are screwed or otherwise secured to 40 the plate E', which rotates in the direction shown by the arrow x in Fig. 3. These different segments consist, first, of a triangular

groove L, having one side open to receive the grain and one side inclined upward to the land M, whereon the grain is split. Beyond 55 this land M is the groove O, opening only to the outer edge of the disk. The wall P shuts off the groove L from the groove O and closes the groove L at the outer edge of the disk. The openings in the ring J are placed at the 60 opening to the triangular groove L, so that the grain passing through the openings H enters into the recesses L (see Figs. 3 and 5) of the segments E, where it is spread over their whole breadth and driven by centrifugal force 65 onto the inclined plane M, where the splitting takes place during its progress to the highest point N, after which the material falls into the recesses O and is taken to the circumference of the plate E' and then drawn to the 70 outlet Q' by the gatherers Q, Q, fixed under the said plate E'. The sides, partitions, or ribs P allow the corn to pass out only by the inclined planes M and prevent it passing unacted upon through the machine.

The above description applies to the decorticating, opening, and splitting of grains of corn or the like; but the apparatus is applicable also for reducing or crushing in the manufacture of grits or the like, similar segments being employed for this purpose, with the necessary increase of working-surface and additional grooves of the proper breadth and angles. The plate or disk E' is rotated by a vertical shaft R, which may be supported 75 in a step-bearing R⁴, and in an upper bearing R' with arms R², bolted onto the brackets R³. The shaft R is driven by a pair of bevel-wheels S from the shaft S² and pulley T. The whole is mounted in a rigid frame-work U. 80 There may be two doors Q², to facilitate the inspection and adjustment of the disks E and F, which adjustment may be effected by means of lever V, operated by the hand-wheel and screwed shaft W for raising the step-bearing 85 R⁴, or by any other suitable adjusting device. The entrance-passages H for the corn between the disks E F, made in the ring J, as shown in Fig. 3, prevent the corn being operated upon before entering the divisions of the segments K, the corn being distributed through these passages to the recesses L, and then a second distribution takes place over the surfaces to the outlet-passages, as aforesaid, and

accumulation of corn on the working-surfaces is avoided. This arrangement presents the advantage of considerable production from the working-surfaces, great economy in the 5 motive power, as friction is reduced, owing to the limited distance traveled by the corn and the manner of spreading the same over the working-surfaces. There are also no 10 shocks resulting from the accumulation of the material, and overheating is also prevented.

The disks or segments E and F may be provided with working-surfaces on each face, so that they can be reversed when desired.

I claim as my invention—

15 1. In a grinding-machine, the combination of a distributing-plate, a removable sieve, a rotating disk having at its outer edge an annular grinding-face with a stationary grinding-disk, a ring provided with openings to 20 allow the grain to pass to the grinding-disks at the proper parts thereof, means for adjusting the grinding-disks relatively to each other, and gatherers, substantially as described.

2. In a grinding-mill, the combination of two removable grinding-disks, the upper one 25 stationary and having serrated surfaces and the lower one rotary and provided with lands and grooves L M N O P, and a ring J, having openings to the grooves L, substantially as and for the purpose described.

3. In a grinding-mill, the combination of two grinding-disks, one of which is rotary and has a series of lands and grooves, with a ring carried by and turning with the said rotating disk and having openings to the proper 35 grooves thereof, substantially as and for the purpose set forth.

In testimony whereof I have signed my name to this specification in the presence of two subscribing witnesses.

AMBROISE MILLOT.
